SEAT UNIT

Carl H. Oermann, York, Pa.

Application December 27, 1940, Serial No. 371,871

3 Claims. (Cl. 5—124)

This invention relates to seat units of the type used in gliders, porch swings, couches, and other articles of furniture for supporting one or more cushions.

The subject matter of the present invention is in part shown and described in my patent application Serial No. 324,311, filed March 16, 1940, and said part is taken from that application in compliance with a requirement of division.

An object of the invention is to provide an improved seat unit in which the spring seat structure is provided with a sheet metal cover or skirt adapted to form a closure for the front of the spring cushion supporting assembly and to be movable upwardly and downwardly therewith.

Another object of the invention is to provide an improved spring seat structure having a panel fastened only to the upper portion of the spring assembly and arranged to extend across the front of the seat structure so as to conceal the springs.

Another object of the invention is to provide an improved spring seat structure having a sheet metal panel extending across the front of the spring assembly so as to conceal the springs, the panel being secured along its upper longitudinal edge to the upper portion of the spring assembly so that when the springs move downwardly and upwardly the panel will move therewith.

Another object of the invention is to provide an improved front closure for the springs of a spring cushion supporting assembly in which the spring closure element is disconnected from the ends of the device and is secured to the spring assembly so as to move downwardly and upwardly therewith.

Other objects and advantages of the present invention will be understood by reference to the following specification and accompanying drawings, wherein there is illustrated a certain selected form of the seat unit construction embodying the present invention.

In the accompanying drawings:

Figure 1 is a perspective view of a glider having a seat unit constructed according to the present invention;

Fig. 2 is an enlarged vertical transverse section taken in a plane between two of the seat cushions shown in Fig. 1 and showing the front portion of the seat unit;

Fig. 3 is a front elevation of a portion of the structure shown in Fig. 1;

Fig. 4 is a plan view showing the manner in which the upper edge portion of the sheet metal panel is secured to the spring cushion assembly;

Fig. 5 is a section taken on the line 5—5 of Fig. 4.

Fig. 6 is a vertical transverse section of the seat unit, showing a modification in the means for retaining the front panel in position with respect to the seat unit; and

Fig. 7 is a plan view of a portion of the structure shown in Fig. 6.

Referring to the drawings, the invention has been shown applied to a glider 111 comprising a back 112, a seat 113, and end portions 114, which are all swingingly suspended from a supporting frame in the manner to be hereinafter more fully described.

15 The seat 113 comprises a lower frame member 115 for supporting a spring seat structure 116, composed of a plurality of coil springs 117 arranged in the usual manner, so as to support one or more cushions 118.

20 The spring seat structure, in addition to the coil springs 117, may have an upper frame member 119 arranged along the upper front edge thereof.

The upper frame member 119 is connected to 25 the upper coils of the springs 117 by means of a suitable fastening device, such as a clip 120 shown in Fig. 4, so as to retain the springs 117 in position in the lower frame member 115, in well known manner.

30 At each end of the glider, the supporting frame is formed with a horizontally extending floor engaging member 121 to which is secured a vertical upright member 122.

The seat 113 is suspended from the stationary 35 end members 122 by means of suspension bands or strap hangers 123 and 124, the strap hangers 123 being connected to the front of the end members 122 and the strap hangers 124 being connected to the rear of said end members, as shown 40 in Fig. 1.

The lower end of each strap hanger 123 is connected to a bar 125 fixed to the lower frame member 115, as shown in Fig. 3.

Likewise, the lower end of each strap hanger 45 124 is connected to a bar 126 fixed to the rear of the seat frame in a manner similar to the bar 125.

Arranged beneath the seat frame and extending longitudinally of the glider, is a bar 127 50 which is connected to the stationary end members 122 by braces 128 and 129 (see Figs. 1 and 3).

Mounted on the upper longitudinal frame member 119 of the spring seat assembly, is the upper longitudinal edge 131 of a skirt or panel 55 132.

The panel 132 is preferably made of thin sheet metal, and may be slightly arcuate in cross section, as shown in Fig. 2. The panel 132 is coextensive with the spring seat assembly and extends downwardly from the upper portion thereof to a point a suitable distance above the floor, so as to provide an apron for concealing the front portion of the glider beneath the cushions 118.

The ends of the panel 132 are spaced from the end portions 114, as shown in Figs. 1 and 3.

The lower edge portion of the panel can have a strip of suitable material 133 applied to the rear face thereof, as shown in Fig. 2. The strip of material 133 serves as a wear surface for engaging the metal parts of the seat frame structure.

For the purpose of attaching the panel 132 to the upper frame member 119, as shown in Figs. 4 and 5, the upper flange 131 of said panel is provided at suitable intervals with openings 134, 20 only one of which is shown.

Secured to the upper frame member 119 of the spring seat assembly, is a plate 135 having an opening 136 therein adapted to be registered with the opening 134. The plate 135 is arranged beneath the flange 131 of the panel 132, and has an eye 137 encircling the upper frame member 119.

A screw bolt 138 is mounted in the aligned openings 134 and 136 with its threaded shank disposed downwards. A nut 139 is screwed on to the threaded shank of the bolt 138, said nut being turned up until it engages the eye 137.

In order to retain the lower portion of the front panel 132 in position and also to prevent the panel from swinging outwardly with respect to the front of the spring seat assembly, an arm or clip 141 is secured at one end 142 to the rear face of the panel 132, as shown in Figs. 2 and 3. Preferably the clip 141 is so arranged that the free portion of said clip extends behind the bar 125. The arm or clip 141 can be spaced slightly from the bar 125, as shown in Fig. 2, but should the panel 132 have a tendency to swing outwardly away from the front of the glider, the arm 141 will engage the bar 125 and thereby limit further outward movement of the panel.

The construction of the panel 132 is such that the lower portion thereof is located at a distance below the spring seat assembly. Since the ends of the panel are disconnected from any portion of the glider frame structure, when the glider is occupied by one or more persons, the weight of whom will compress the springs 117 and will at the same time force the upper frame member 119 55 downwardly towards the lower frame member 115, the panel 132 will also be moved downwardly, since the panel is connected along its upper edge to the upper frame member 119. This downward and upward movement of the panel is in a substantially vertical plane.

In the form of the invention shown in Figs. 6 and 7, the means for retaining the front panel in position with respect to the seat unit is shown as comprising a bar 146, the front end of which is rigidly secured to the panel 132 at a point directly beneath the lower frame member 115, as indicated at 147, Fig. 6.

The supporting means for the springs 117 may include rods 148 and 149, the rods 148 extending 70 lengthwise of the seat unit and the rods 149 extending transversely of the seat unit or at right angles to the rods 148.

The bar 146 may extend from the panel 132 rearwardly to the central portion of the seat unit 75

and may be connected to the intermediate rod 148 by means of an eye 150 formed on the end portion of said bar and encircling the rod 148.

By pivotally connecting one end of the bar 146 5 to the rod 148 and rigidly attaching the other end of said bar to the panel 132, when the seat unit is occupied and the springs 117 are compressed and the panel 132 is moved downwardly with the springs, as has been heretofore described, the bar 146 will retain the panel 132 in such relation to the spring seat unit that said panel is prevented from swinging outwardly or inwardly with respect to the lower frame member 115. Since the lower frame member 115 is not moved relatively to the seat unit structure when the springs 117 are compressed or otherwise flexed, the relation of the lower frame member 115 to the ends 114 always remains the same, and when the springs 117, after being compressed, expand to their normal uncompressed position and thus cause the panel 132 to slide upwardly with respect to the lower frame member 115, the upward movement of the panel 132 will be limited when the bar 146 strikes the lower edge of the lower frame member 115. It will, therefore, be noted that the bar 146 retains the panel 132 in the desired position at the front of the seat unit and prevents said panel from moving laterally and also upwardly an excessive amount with respect to the seat unit.

Having thus described my invention, what I claim is:

1. A seat unit comprising a spring cushion supporting assembly including an upper frame member and a lower frame member and a plurality of spring elements secured within said members for supporting upon the top thereof one or more cushions, the upper frame member being movable downward towards the lower frame member when the seat is occupied and the springs are compressed, and a single sheet metal panel extending the length of the assembly and secured along its upper longitudinal edge to the upper frame member and extending downwardly to a point below the lower frame member of the seat unit so as to conceal the spring elements, the lower longitudinal edge of said panel being free of connection to the lower frame member, said panel being movable as a unit with said upper frame member so that the relation of said panel with respect to the cushion on said seat unit remains substantially the same at all times.

2. A seat unit comprising a spring cushion supporting assembly including an upper frame member and a lower frame member and a plurality of spring elements secured within said members for supporting upon the top thereof one or more cushions, the upper frame member being movable downward towards the lower frame member when the seat is occupied and the springs are compressed, a single sheet metal panel extending the length of the assembly and secured along its upper longitudinal edge to the upper frame member and extending downwardly to a point below the lower frame member of the seat unit so as to conceal the spring elements, the lower longitudinal edge of said panel being free of connection to the lower frame member, said panel being movable as a unit with said upper frame member so that the relation of said panel with respect to the cushion on said seat unit remains substantially the same at all times, a bar fixed to the lower frame member and projecting therefrom for attachment to suspension means adapted to swingingly support the seat

unit from a stationary support, and means secured to said panel and engageable with the bar for limiting outward swinging of the panel with respect to the front of the seat unit.

3. A seat unit comprising a spring cushion supporting assembly including an upper frame member and a lower frame member and a plurality of spring elements secured within said members for supporting upon the top thereof one or more cushions, the upper frame member being movable downward towards the lower frame member when the seat is occupied and the springs are compressed, a single sheet metal panel extending the length of the assembly and secured along its upper longitudinal edge to the upper

5 frame member and extending downwardly to a point below the lower frame member of the seat unit so as to conceal the spring elements, the lower longitudinal edge of said panel being free of connection to the lower frame member, said panel being movable as a unit with said upper frame member so that the relation of said panel with respect to the cushion on said seat unit remains substantially the same at all times, and 10 means secured to said panel and operatively connected with the lower frame member for limiting movement of the panel with respect to the front of the seat unit.

CARL H. OERMANN.
